UNITED STATES PATENT OFFICE

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-SIGNALING SYSTEM

Application filed April 22, 1929. Serial No. 356,908.

My invention relates to railway signaling systems of the type involving light signals.

One feature of my invention is the provision of means for preventing a signal from 5 momentarily giving a proceed indication when the indication should change from stop to caution, and another feature of my invention is the provision of means for preventing a signal from momentarily giving the 10 stop indication when the indication should change from caution to proceed or vice versa.

I will describe four forms of signaling systems embodying my invention, and will then point out the novel features thereof in 15 claims.

In the accompanying drawings, Fig. 1 is a diagrammatic view showing one form of 20 signaling system embodying my invention. Figs. 2, 3 and 4 are views showing modifications of the system shown in Fig. 1 and also embodying my invention.

Similar reference characters refer to similar parts in each of the several views.

Referring first to Fig. 1, the reference 25 characters 10 and 10^a designate the track rails of a stretch of railway track along which traffic normally moves in the direction indicated by the arrow. These rails are divided by insulated joints 5 into blocks 1—2, 2—3, 3—4, 30 etc., and, as here shown, each block is further divided by insulated joints 5 to form two track sections, such as 1—1^a and 1^a—2. Each track section is provided with a track circuit comprising a battery 37 connected with the 35 rails adjacent one end of the section, and a track relay connected with the rails adjacent the other end of the section and designated by the reference character T with a distinguishing exponent.

40 Located adjacent the entrance end of each block is a signal designated by the reference character S with an exponent corresponding to the location. Each signal is of the light type, and, as here shown, is of what is known 45 as the searchlight type of signal. Each of these signals comprises a member 6 mounted to oscillate and controlled by two windings 7 and 8. The member 6 carries three roundels G, R and Y, arranged to co-operate with 50 an electric lamp C in such manner that when

the member 6 is in its middle position, to which it is biased, roundel R is in front of the lamp C, whereas when the member 6 is swung to the left or to the right, roundel Y or roundel G is placed in front of the lamp C. As shown in the drawing, the lamp C is above the roundels, but the lamp is placed in this location for purposes of illustration, and in actual practice it is understood that the lamp is located directly behind the roundels. 55 The signal is in its "proceed", "caution" or "stop" position according as the roundel G, Y or R is located in front of the lamp C. The signal indicates "proceed", "caution" or "stop" according as it is in its proceed, caution or stop position when lamp C is lighted. Operatively connected with the member 6 are two contacts 9^a and 9^y, which contacts are operated in such manner that when the signal is in its stop position both contacts are 60 open, when the signal is in its caution position contact 9^y is closed and 9^a is open, whereas when the signal is in its proceed position, contact 9^a is closed and 9^y is open. A signal 65 of the type thus described is disclosed and claimed in re-issue Letters Patent of the United States No. 14,940, granted to Eli J. Blake on August 31, 1920.

Associated with each signal S is an approach lighting relay A, and an auxiliary relay P which, as here shown, is a pole changing relay. Relay P is constructed to be slow releasing so that it will not open its front contacts when the associated signal changes from the caution to the proceed position or 70 conversely.

75 Winding 7 of each signal S is constantly supplied with current from a suitable source such, for example, as a battery which is not shown in the drawing, but the terminals of which are designated B and O. The other winding 8 of each signal is controlled by the track relays for the corresponding block, and also by the relays A and P for the block 80 next in advance. Referring to signal S¹, for example, the circuit for winding 8 is from terminal B, through the winding of relay A², front point of contact 13 of relay P², contact 11 of track relay T², contact 11 of track relay T¹, winding 8 of signal S¹, and the front point 85

90 95 100

of contact 14 of relay P² to terminal O. Relay P² being energized, current of what I will term "normal" polarity is supplied to winding 8 of signal S¹, and this signal is then in its proceed position. When relay P² is de-energized, current of reverse polarity is supplied to winding 8 and the signal then changes to its caution position.

The circuit for relay P² is from terminal B, through front contact 22 of relay A², contact 12 of track relay T³, contact 9^G or 9^Y of signal S², and the winding of relay P² to terminal O.

Each signal lamp C is controlled by a back contact of the associated approach lighting relay A. Referring to signal S², for example, the circuit for lamp C is from terminal B, through back contact 16 of relay A², and the lamp C to terminal O. It follows that each signal lamp is extinguished except when the associated approach lighting relay is de-energized.

As shown in the drawing, track section 3—3^a is occupied by a train W, so that track relay T⁵ is de-energized, with the result that winding 8 of signal S³ is de-energized, so that this signal is in its stop position. Relay P³ is likewise de-energized because its circuit is open at contact 12 of track relay T⁵, and also at the contacts 9 on signal S³, so that current of reverse polarity is supplied to winding 8 of signal S², with the result that this signal is in its caution position. Relay P² is therefore energized, so that current of normal polarity is supplied to winding 8 of signal S¹, with the result that this signal is in its proceed position.

When the train W passes into track section 3^a—4, track relay T⁵ will become energized and track relay T⁶ will become de-energized, so that no change will occur in the conditions of the signals or of relays A and P. When the train passes point 4, however, track relay T⁷ will become de-energized and track relay T⁶ will become energized, so that current of reverse polarity will be supplied to winding 8 of signal S³, with the result that this signal will change to the caution position. At this point it should be noted that the circuit for relay P⁴ includes a front contact 22 of the approach lighting relay A⁴. In the event of a light engine passing point 4 at high speed, it is possible for track relay T⁶ to close at the same moment that track relay T⁷ opens, and in the absence of contact 22 from the circuit for relay P⁴ it might be possible for the latter relay to remain closed for a brief interval after track relay T⁶ closes, in which event signal S³ would momentarily assume its proceed position before changing to the caution position. By including contact 22 in the circuit for relay P⁴, however, the latter relay becomes de-energized as soon as a train enters block 3—4, because the circuit for relay A⁴ is opened at contact 11 of track relay T⁶, and so when a light engine or a train passes point

4, relay P⁴ is already de-energized and therefore signal S³ will change from the stop to the caution position without momentarily assuming its proceed position.

Relay P⁴ will remain de-energized as long as the train occupies the block to the right of point 4, because both contacts 9^G and 9^Y of signal S⁴ are open. When the train passes out of such block, signal S⁴ will change to the caution position, so that contact 9^Y will become closed, with the result that relay P⁴ will become energized and signal S³ will then change to the proceed position.

Referring now to Fig. 2, the track circuits and signals shown in this view are the same as in Fig. 1, but winding 8 of each signal is controlled locally by a signal relay designated by the reference character L with an exponent corresponding to the location. Referring to relay L¹, for example, and assuming that the parts are in the positions shown in the drawing, the circuit for this relay is from terminal B, through the winding of approach lighting relay A², front point of contact 32 of track relay T³, front point of contact 34 of relay P², contacts 11 of track relays T² and T¹, winding of relay L¹, front point of contact 35 of relay P², and front point of contact 33 of track relay T³ to terminal O. Relay P² is energized by its circuit passing from terminal B, through contact 27 of relay L², contact 9^Y of signal S², and the winding of relay P² to terminal O. Relay P² being energized, current of normal polarity is supplied to line relay L¹. When relay P² is de-energized, the circuit is the same as before, except that the pole changing contacts 34 and 35 of this relay will reverse the polarity of the current supplied to relay L¹. When relay L¹ is energized in the normal direction, winding 8 of signal S¹ is also energized in the normal direction, the circuit being from terminal B, through neutral contact 28, polar contact 29, winding 8 and polar contact 30 to terminal O. When relay L¹ is energized in the reverse direction, the circuit for winding 8 is from terminal B, through neutral contact 28, polar contact 30, winding 8 and polar contact 29 to terminal O. These circuits are so arranged that winding 8 is energized in the normal or reverse direction according as the relay L¹ is energized in the normal or the reverse direction, so that signal S¹ is in its proceed or caution position according as relay L¹ is energized in the normal or the reverse direction. The circuits for winding 8 are provided with a shunt around neutral contact 28 of relay L¹, which shunt includes front contact 31 of relay P¹. The purpose of this shunt will appear hereinafter.

When track relay T³ is de-energized, an auxiliary circuit for relay L¹ is closed, which circuit passes from terminal B, through the winding of relay A², back contact 32 of track relay T³, winding of relay L¹, contacts 11

of track relays T^1 and T^2 , back point of contact 33 of track relay T^3 to terminal O. When this circuit is closed, current of reverse polarity is supplied to relay L^1 regardless of the condition of pole changing relay P^2 .

5 Lamp C of each signal is controlled by a back contact 16 of the associated approach lighting relay A as shown in Fig. 1.

As shown in the drawing, section 3-3^a is 10 occupied by a train W, so that track relay T^5 is de-energized, with the result that relay L^3 is de-energized, and signal S^3 is in its stop position. Current of reverse polarity is supplied to relay L^2 through the back points of contacts 32 and 33 of track relay T^5 , so that signal S^2 is in its caution position. Relay P^2 being energized, current of normal polarity is supplied to relay L^1 , so that signal S^1 is in its proceed position.

20 When train W passes point 4, track relay T^6 will close and track relay T^7 will open. The opening of track relay T^7 will cause signal S^4 to display the stop indication, but relay P^4 being slow acting in character will 25 remain closed for a short interval of time, so that in the absence of preventative means relay L^3 might be energized in the normal direction for a brief interval of time, with the result that signal S^3 might momentarily 30 assume the proceed position before changing to the caution position. To prevent this, I have provided the branch path including the back points of contacts 32 and 33 of track relay T^7 for the circuit of relay L^3 , by virtue 35 of which relay L^3 becomes energized in the reverse direction immediately upon the opening of track relay T^7 . It follows that signal S^3 will change from the stop to the caution position without momentarily assuming the 40 proceed position.

When the train passes out of the block to the right of point 4, relay P^4 will become energized, thereby reversing the polarity of the current supplied to relay L^3 . This will cause the neutral contacts of relay L^3 to open momentarily while the polar armature of relay L^3 is reversing, with the result that signal S^3 might momentarily assume the stop position prior to assuming the proceed position. To prevent this, I have provided the shunt, hereinbefore referred to, around neutral contact 28 of relay L^3 , which shunt includes front contact 31 of relay P^3 . During the time that the neutral contact 28 of relay L^3 is open, the circuit for winding 8 of signal S^3 is maintained through contact 31 of relay P^3 , with the result that this signal changes directly from the caution position to the proceed position without momentarily assuming the stop position.

Referring now to Fig. 3, the track circuits and the signals are the same as in Fig. 1, but in Fig. 3 each signal is controlled by a home relay H and a distant relay D. Referring to signal S^1 , for example, the circuit for home

relay H^1 is from terminal B, through the winding of approach lighting relay A², contact 11 of track relay T^2 , contact 11 of track relay T^1 , and the winding of relay H^1 to terminal O. It follows that relay H^1 and relay A² will each be energized or de-energized according as block 1-2 is unoccupied or occupied. The circuit for distant relay D¹ is from terminal B, through contact 19 of home relay H², contact 23 of auxiliary relay P², contact 17 of home relay H¹, and the winding of relay D¹ to terminal O. The circuit for relay P² is from terminal B, through front contact 22 of relay A², contact 9^G or 9^Y of signal S², and the winding of relay P² to terminal O. When relays H¹ and D¹ are both energized, current of normal polarity is supplied to winding 8 of signal S¹, the circuit being from terminal B, through the front contact 20 of relay D¹, front contact 18 of relay H¹, winding 8, and front contact 21 of relay D¹ to terminal O. When distant relay D¹ is de-energized, the circuit is the same as before, except that pole-changing contacts of relay D¹ are reversed, so that current of reverse polarity is supplied to winding 8, and signal S¹ assumes the caution position. Of course, when relay H¹ is de-energized, the circuit for winding 8 is open, so that signal S¹ is in its stop position.

90 Lamp C for each signal is controlled by a back contact 16 of the associated approach lighting relay A as in Fig. 1.

95 As shown in the drawing, a train W occupies block 3-4, so that signal S³ is in the stop position, signal S² is in the caution position, and signal S¹ is in the proceed position. Approach lighting relay A⁴ is de-energized, so that lamp C of signal S⁴ is lighted and relay P⁴ is de-energized. Signal S⁴ now indicates proceed. When the train W passes point 4, the circuit for home relay H³ will be closed, but relay P⁴ already being de-energized, the circuit for relay D³ cannot close momentarily even if relay H⁴ should remain closed until after track relay T⁶ becomes closed, so that signal S³ cannot momentarily assume the proceed position before changing to the caution position.

100 Referring now to Fig. 4, each block comprises only one track section, and this track section is provided with a track circuit including a battery 37 and track relay T and an approach lighting relay A interposed between the battery 37 and one track rail, so that each approach lighting relay is normally de-energized or becomes energized when a train enters the block. Consequently, the circuit for lamp C of each signal in this view includes a front contact 36 of the associated approach lighting relay A instead of a back contact of the corresponding relay, as in the preceding views.

105 The track relay T for each block serves as the home relay for the associated signal, and each signal is provided with a distant relay D 110

as in Fig. 3. The circuit for distant relay D^1 , for example, is from terminal B, through contact 26 of track relay T^3 , contact 24 of auxiliary relay P^2 , contact 11 of track relay T^1 , and the winding of relay D^1 to terminal O. The circuit for relay P^2 is from terminal B, through back contact 15 of approach lighting relay A^2 , contact 9^g or 9^y of signal S^2 , and the winding of relay P^2 to terminal O.

Block 3-4 is occupied by a train W, so that signal S^3 is in its stop position, signal S^2 is in the caution position, and signal S^1 is in the proceed position. Approach lighting relay A^4 is closed so that lamp C of signal S^4 is lighted and indicates proceed, and relay P^4 is de-energized. When the train W passes point 4, it follows that relay D^3 can not momentarily be energized to cause signal S^3 to momentarily assume the proceed position, even if contact 26 of track relay T^7 remains closed until after contact 11 of track relay T^5 closes, because relay P^4 is already open. It follows that signal S^3 will change directly from the stop position to the caution position without momentarily assuming the proceed position.

Although I have herein shown and described only a few forms of signaling systems embodying my invention, it is understood that various changes and modifications may be made therein within the scope of the appended claims without departing from the spirit and scope of my invention.

Having thus described my invention, what

I claim is:—

1. In combination, a stretch of railway track divided into blocks, track circuits including track relays for said blocks, a signal for each block responsive to reversals of polarity of the current supplied thereto, an approach lighting relay and a pole changing relay associated with each signal, a line circuit for each signal controlled by each track relay for the associated block and including the winding of said approach lighting relay for the next signal in advance as well as the contacts of said pole changing relay for such signal in advance, and a circuit for each pole changing relay controlled by a track relay for the associated block and by a front contact of the associated approach lighting relay.

2. In combination, a stretch of railway track divided into blocks, track circuits including track relays for said blocks, a signal for each block responsive to reversals of polarity of the current supplied thereto, an approach lighting relay and a pole changing relay associated with each signal, a line circuit for each signal controlled by each track relay for the associated block and including the winding of said approach lighting relay for the next signal in advance as well as the contacts of said pole changing relay for such signal in advance, and a circuit for each pole

changing relay controlled by a track relay for the associated block and by a front contact of the associated approach lighting relay as well as by a contact operated by the associated signal and closed only when such signal gives a proceed indication.

3. In combination, a stretch of railway track divided into blocks, track circuits including track relays for said blocks, a signal for each block responsive to reversals of polarity of the current supplied thereto, an approach lighting relay and a pole changing relay associated with each signal, a line circuit for each signal controlled by each track relay for the associated block and including the winding of said approach lighting relay for the next signal in advance as well as the contacts of said pole changing relay for such signal in advance, a circuit for each pole changing relay controlled by a track relay for the associated block and by a front contact of the associated approach lighting relay, and a lamp for each signal controlled by a back contact of the associated approach lighting relay.

4. In combination, a stretch of railway track divided into blocks, track circuits including track relays for said blocks, a pole changing relay and an approach lighting relay for each block, a signal circuit for each block controlled by each track relay for the block and including the contacts of the pole changing relay for the block next in advance as well as the winding of the approach lighting relay for the latter block, a signal for each block controlled by said signal circuit for the block and responsive to the polarity of the current supplied thereto, a circuit for each pole changing relay controlled by a track relay for the associated block, and a lamp for each signal controlled by a back contact of the associated approach lighting relay.

5. In combination, a stretch of railway track divided into blocks, track circuits including track relays for said blocks, a pole changing relay and an approach lighting relay for each block, a signal circuit for each block controlled by each track relay for the block and including the contacts of the pole changing relay for the block next in advance as well as the winding of the approach lighting relay for the latter block, a signal for each block controlled by said signal circuit for the block and responsive to the polarity of the current supplied thereto, and a circuit for each pole changing relay controlled by a track relay and by the approach lighting relay for the associated block.

6. In combination, a stretch of railway track divided into blocks, track circuits including track relays for said blocks, a pole changing relay and an approach lighting relay for each block, a signal circuit for each block controlled by each track relay for the

- block and including the contacts of the pole changing relay for the block next in advance as well as the winding of the approach lighting relay for the latter block, a signal for 5 each block controlled by said signal circuit for the block and responsive to the polarity of the current supplied thereto, a circuit for each pole changing relay controlled by a track relay for the associated block and by a 10 contact associated with the corresponding signal and closed only when the signal gives a proceed indication, and a lamp for each signal controlled by a back contact of the associated approach lighting relay.
- 15 7. In combination a stretch of railway track divided into blocks, a signal for each block, an approach lighting relay for each signal responsive to the presence of a train in the block next in the rear, an auxiliary 20 relay associated with each signal and controlled by contacts operated by the signal and also by the approach lighting relay for such signal, and a circuit for each signal controlled by traffic conditions in the associated 25 block and by the auxiliary relay for the signal next in advance.
8. In combination, a stretch of railway track divided into blocks, track circuits including track relays for said blocks, a pole- 30 changing relay for each block controlled by each track relay for the block, a signal circuit for each block controlled by the track relays for the block and including the contacts of the pole-changing relay for the block 35 next in advance whereby current of normal or reverse polarity is supplied to such circuit according as the pole-changing relay is energized or de-energized, means operating when a track relay is de-energized to supply 40 current of reverse polarity to the signal circuit for the block next in the rear regardless of the condition of the pole-changing relay which normally controls such circuit, and a signal for each block controlled by the associated signal circuit to indicate proceed or 45 caution according as such circuit is supplied with current of normal or reverse polarity.
9. In combination, a stretch of railway track divided into blocks, track circuits including track relays for said blocks, a pole- 50 changing relay for each block, a signal relay for each block responsive to the polarity of the current supplied thereto, a line circuit for each signal relay controlled by each track 55 relay for the associated block and including the pole-changing contacts of the pole-changing relay for the block next in advance whereby current of normal or reverse polarity is supplied to such circuit according as the pole- 60 changing relay is energized or de-energized, means operating when a track relay is de-energized to supply current of reverse polarity to the line circuit for the block next in the rear regardless of the condition of the 65 pole-changing relay which normally controls such circuit, a signal for each block controlled by the associated signal relay and arranged to indicate proceed or caution according as such relay is energized with current of normal or reverse polarity, and means for controlling each pole-changing relay by the associated signal and by a track relay for the associated block.
10. In combination, a stretch of railway track divided into blocks, track circuits including track relays for said blocks, a pole-changing relay for each block, a signal relay for each block responsive to the polarity of the current supplied thereto, a line circuit for each signal relay controlled by each track 70 relay for the associated block and including the pole-changing contacts of the pole-changing relay for the block next in advance whereby current of normal or reverse polarity is supplied to such circuit according as the pole-changing relay is energized or de-energized, means operating when a track relay is de-energized to supply current of reverse polarity to the line circuit for the block next in the rear regardless of the condition of the pole-changing relay which normally controls such circuit, a signal for each block controlled jointly by the associated pole-changing relay and by the associated signal relay and arranged to indicate proceed or caution according as such signal relay is energized with current of normal or reverse polarity, and means for controlling each pole-changing relay by the associated signal and by a track relay for the associated block.
- In testimony whereof I affix my signature.
- LESTER E. SPRAY.
